TRAJECTORY SPOUT FITTING

Raymond W. Young, Louisville, Ky., assignor to American Standard Inc., New York, N.Y., a corporation of Delaware

Filed Jan. 3, 1969, Ser. No. 15,195

Term of patent 14 years

Int. Cl. D23—01

U.S. Cl. D23—32

Fig. 4.

Fig. 5.

Fig. 6.

FIG. 1 is a side elevational view of a trajectory spout fitting embodying my new design;

FIG. 2 is a front elevational view thereof;

FIG. 3 is a bottom plan view thereof;

FIG. 4 is a view as seen from line 4—4 of FIG. 1;

FIG. 5 is a cross sectional view taken on line 5—5 of FIG. 2; and

FIG. 6 is a perspective view thereof.

I claim:

The ornamental design for a trajectory spout fitting, substantially as shown.
